CLAIM

The ornamental design for a compartmented carton insert, as shown and described.

DESCRIPTION

FIG. 1 is a perspective view of a compartmented carton insert showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof showing the compartmented carton insert in use with an exemplary carton;

FIG. 9 is a perspective view of a second embodiment of a compartmented carton insert, showing our new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is another perspective view thereof showing the compartmented carton insert in use with an exemplary carton.

The dash-dash broken lines are shown for the purpose of illustrating environmental subject matter of an exemplary carton and form no part of the claimed design.
